UNITED STATES PATENT OFFICE

HAROLD H. TIMIAN, OF KOKOMO, INDIANA.

FUEL-VAPORIZING ATTACHMENT FOR INTERNAL-COMBUSTION ENGINES

Application filed July 23, 1921. Serial No. 487,160.

To all whom it may concern:

Be it known that I, HAROLD H. TIMIAN, a citizen of the United States of America, residing at Kokomo, in the county of Howard and State of Indiana, have invented certain new and useful Improvements in Fuel-Vaporizing Attachments for Internal-Combustion Engines, of which the following is a specification, reference being had 10 therein to the accompanying drawings.

The invention relates to fuel vaporizers for internal combustion engines and has for its object the obtaining of an exceedingly simple construction which is attachable to any construction of multi-cylinder engine having the inlet and exhaust manifolds on the same side. To this end the invention consists in a member which is insertable between the manifolds and the engine block through which the heat of the exhaust gases is transferred to the incoming mixture. The invention further consists in so constructing the member that the amount of heat transferred is greatest 20 when the engine is idling or running at low speed, lessening at higher speeds.

In the drawings:

Figure 1 is a horizontal section through a portion of the engine block and manifolds 30 showing my attachment in position;

Figure 2 is a front elevation of the attachment;

Figure 3 is a cross-section therethrough on the line 3—3 of Figure 1.

While my improvement is applicable to various types of multi-cylinder internal combustion engines, I have shown the specific construction applicable to a Ford car, in which A is the engine block, B the intake manifold, and C the exhaust manifold. D are clamping yokes for holding the manifolds upon the block, and E are the tap bolts for securing said clamps.

My attachment comprises a hollow member F, which is insertable between the manifolds and the block, and of a length to extend between and cover a pair of the port openings G and G' in the block for the exhaust gases, as well as the intermediate 50 port opening H for the intake gases. This

member is preferably a cored casting. It is provided with the central transverse passage I which registers with the port opening H and the corresponding portion of the intake manifold B, this passage being surrounded by a wall which separates the same from the chamber within the casting. The member is further provided with apertures J and J' for registration with the ports G and G' and the corresponding portions of the exhaust manifold C. These apertures open into the chamber within the hollow casting through which communication is established between the ports G and G', said passage surrounding the wall forming the 60 passage I. The apertures J and J' on the side which abuts against the engine block are preferably of the full area of the ports G and G', but the apertures on the opposite side of the member F are preferably slightly 70 restricted as by the baffle segments K and K'. These act as deflectors for causing a portion of the gases discharged from the exhaust port in the block to pass through the chamber over to the other end of the hollow member and through the port in the exhaust manifold at that point. The member F is further apertured at L and L' for passage of the clamping screws E and these apertures are surrounded by walls M and M' 80 which separate the same from the chamber within the casting.

With the construction as described, to attach the vaporizer to the engine it is merely necessary to loosen the clamping 85 bolts E, separating the manifolds from the block and inserting the member F therebetween. The bolts E are then replaced and are tightened to clamp the manifolds firmly against the member F and the latter against 90 the block. In operation, when the engine is idling or operating at low speeds, the exhaust gases which are alternately discharged through the ports G and G' will have a portion thereof deflected by the segment K or K', which portion will pass through the chamber, surrounding the passage I and over to the other exhaust port where it will be discharged into the manifold. The gases thus passing through the 100

chamber will transfer heat to the wall surrounding the passage I so that the indrawn combustible mixture will be heated and the liquid fuel vaporized. To facilitate this vaporization of the liquid the port I' of the passage I, which is upon the block side of the member F, is of the full area of the port H in the block, while the port I² on the opposite side of the member F is of the area of the manifold opening which is less than that of the port H. This will cause an eddying of the intake gases in the passage I, which will bring the liquid content of the mixture against the heated walls of said passage, causing vaporization.

When the speed of the engine is increased and the time interval between impulses from the different cylinders is lessened, the pressure within the exhaust manifold becomes more nearly uniform throughout its length, which will lessen the amount of gas deflected through the chamber in the member F. In other words, when the engine is operating at higher speeds, this differential lessens so that the gases do not surge through the member F. Consequently, the amount of heat transferred to the intake gases is lessened, which is precisely the result desired when the engine is operating at high speeds.

With a four cylinder engine, such as the Ford, there are usually six ports in the block, four of which are for the exhaust gases and two for the intake gases. With such a construction two of the members F are used, each one embracing a pair of the exhaust ports and a single intake port. I also preferably make the member F of a cross-section slightly tapering from top to bottom so that the position of the carburetor will not be greatly changed by the lateral displacement of the intake manifold.

What I claim as my invention is:

1. The combination with a multi-cylinder internal combustion engine and intake and exhaust manifolds therefor, of a chambered member forming an auxiliary exhaust passage and insertable between said manifolds and engine for transferring heat from the exhaust gases to the fuel mixture.

2. The combination with a multi-cylinder internal combustion engine and intake and exhaust manifolds therefor, of a hollow member forming an auxiliary exhaust passage and insertable between said manifolds and the engine having a wall for separating the fuel mixture and the exhaust gases through which heat may be transferred from the one to the other.

3. The combination with a multi-cylinder internal combustion engine and intake and exhaust manifolds therefor, of a member insertable between said manifolds and the engine and embracing a pair of exhaust ports and an intake port, said member being

hollow and establishing communication between said exhaust ports and being provided with a wall for separating said passage from the intake passage through which heat is transferable.

4. The combination with a multi-cylinder internal combustion engine and intake and exhaust manifolds therefor, of a member insertable between said manifolds and the engine embracing a pair of exhaust ports, and an intermediate intake port, said member being hollow to form a connecting passage between said exhaust ports and having a transverse intake passage therethrough formed by a wall which is surrounded by said exhaust passage.

5. The combination with a block of a multi-cylinder engine having a plurality of exhaust ports therein and an intermediate intake port, intake and exhaust manifolds, and clamping means for securing said manifolds to the block, of a member insertable between said manifolds and block embracing a pair of said exhaust ports and the intermediate intake port, said member being hollow and forming a transfer passage between said exhaust ports with an intake passage surrounded by said exhaust passage, and apertures through said member separated from said exhaust passage for the passage of the clamping means for said manifolds.

6. A vaporizing attachment for internal combustion engines comprising a hollow member insertable between the engine block and the intake and exhaust manifolds therefor, said member embracing a pair of exhaust ports and forming a connecting passage there-between and being further provided with an intake passage separated from said exhaust passage by a wall through which heat may be transferred, and baffling means for deflecting a portion of the gases from direct passage from the block to the manifold, whereby said gases will surge through said hollow member and transfer their heat to the intake gases.

7. A vaporizing attachment for internal combustion engines comprising a hollow member insertable between the engine block and the intake and exhaust manifolds, said member being ported for direct communication between the ports of the block, and registering ports of the manifold, and also forming a connecting passage between a plurality of exhaust ports surrounding the passage between the intake ports, and baffling means in the ports connecting directly with the exhaust manifold for causing a surging of a portion of the gases through said member to the opposite exhaust port.

8. A vaporizing attachment for internal combustion engines comprising a hollow member insertable between the engine block

and the intake and exhaust manifolds, said member embracing a plurality of exhaust ports and an intermediate intake port, and being provided with registering apertures for the ports in the block and manifolds, the apertures for the intake port being connected by an annular wall and the apertures for the exhaust port

communicating with a chamber within said hollow member which surrounds said annular wall, and baffles for the exhaust ports communicating with the manifold for deflecting a portion of the gases through said hollow member. 10

In testimony whereof I affix my signature. 15
HAROLD H. TIMIAN.
